UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

STEEL RETAINER.

Application filed August 7, 1926. Serial No. 127,953.

This invention relates to rock drills, but more particularly to a steel retainer for fluid actuated rock drills of the hammer type.

The objects of the invention are to prevent 5 ejection of the drill steel from the drill, to insure against accidental displacement of the retaining yoke, and to simplify the construction of retainers of this type.

Other objects will be in part obvious and 10 in part pointed out hereinafter.

The invention consists of the combination 15 of elements, arrangement of parts, and features of construction substantially as hereinafter described and more particularly 15 pointed out in the appended claims and illustrated in the accompanying drawings, in which.

Figure 1 is a sectional elevation of so much 20 of a rock drill as will serve to illustrate the invention,

Figure 2 is a side elevation of the front 25 end of a rock drill showing the retainer in its retaining position,

Figure 3 is an end view of a rock drill 30 showing the manner in which the yoke cooperates with the collar of the drill steel for preventing ejection of the drill steel from the front head of the drill, and

Figure 4 is an end view of the retainer 35 bearing.

Referring to the drawings, the invention is shown applied to a rock drill in which only a front head A, a front cylinder washer B and the front end of a cylinder C are shown. 35 A drill steel D having a collar E is supported by the front head A and has a shank F which extends into the path of an anvil block G guided by the front cylinder washer B for transmitting the blows of the hammer 40 piston H to the drill steel D. The parts comprising the casing of the drill, namely the front head A, the front cylinder washer B, and the cylinder C are in this instance held in assembled relationship by side bolts J 45 which extend through suitable lugs K on the rearward end of the front head A.

In the present instance the side bolts J are of a length to extend well forwardly of the lugs K for the reception of springs L 50 which serve to cushion relative longitudinal movement of the front head A with respect to the cylinder C.

In drills of the type to which the present 55 invention relates, means are usually provided exterior of the drill for preventing ejection

of the drill steel from the drill. Such means are particularly desirable when the drill is being used for drilling thin layers of material such as concrete pavements, or walls in which the drill steel readily penetrates the 60 material and upon the decrease of resistance against the drill bit, the hammer piston tends to force the drill steel out of the front head. In order to at all times insure the retention of the drill steel in the front head, a yoke 65 O is adapted to partly encircle the drill steel D forwardly of the collar E and has rearwardly extending side arms P, the free ends of which are provided with inwardly extending lateral hooks Q which cooperate rotatively with apertures R of bearings S. These bearings S are provided with longitudinal apertures T to cooperate slidably with the side bolts J whereon they are mounted, said side bolts J being of sufficient 70 length to enable the bearings S to be arranged between the lugs K of the front head A and the springs L whereby the said bearings are constantly pressed against the lugs K. In this way the springs L also serve 75 as adequate cushioning means for the yoke O.

In order that the yoke O may at all times be held against accidental displacement from its retaining position, the bearings S are 80 provided with longitudinal grooves U which cooperate with the side arms P for preventing oscillation of the yoke O. The grooves U extend on both sides of the apertures R thus rendering the bearings S reversible and 85 interchangeable on the side bolts J.

It is to be noted that the free ends of the side arms P are so spaced with respect to each other that when the hooks Q are inserted in the apertures, it will be necessary 90 to spread the side arms P somewhat. In this way a certain spring effect will be obtained in the side arms and the yoke which will be sufficient at all times to hold the side arms P in engagement with the grooves U.

The foregoing described retainer permits of several methods of assembling the same on the rock drill. A convenient method consists in inserting the hooks Q in the apertures R of the bearings S and then 105 mounting the bearings on the side bolts J. The side bolts J, together with the retainer and its bearings, may then be attached to the rock drill in the usual manner. If, after the retainer has been secured to the rock 110

drill, breakage of the yoke O should occur, another yoke may be readily substituted therefor by merely inserting one of the hooks in one of the bearings S and then spreading the arms P for the insertion of the other hook in the opposite bearing.

During the operation of the drill, whenever it is desired to remove the drill steel from the front head, the yoke O may be 10 oscillated about the hooks Q until the side arms P are rocked out of the grooves U. Such movement of the retainer will remove the yoke from the path of the collar E of the drill steel D and the drill steel D may then 15 be withdrawn from the front head and another steel substituted therefor.

I claim:

1. In a rock drill, the combination of a cylinder, a front head for the cylinder, a 20 drill steel extending into the front head, side bolts for securing the front head to the cylinder, a yoke for preventing ejection of the drill steel from the front head, side arms on the yoke, hooks on the side arms, and 25 bearings slideable on the side rods to rotatably receive the hooks for supporting the side arms in a plane offset from the longitudinal axis of the front head, said bearings being reversible with respect to the side 30 bolts.

2. In a rock drill, the combination of a cylinder, a front head for the cylinder, a 35 drill steel extending into the front head, side bolts for securing the front head to the cylinder, a yoke for preventing ejection of the drill steel from the front head, side arms on the yoke, inwardly extending lateral hooks 40 on the side arms, and bearings slideable on the side rods, said bearings having apertures to rotatably receive the hooks for supporting the side arms in a plane offset from the longitudinal axis of the front head.

3. In a rock drill, the combination of a cylinder, a front head for the cylinder, a 45 drill steel extending into the front head, side bolts for securing the front head to the cylinder, a yoke for preventing ejection of the drill steel from the front head, side arms on the yoke, inwardly extending lateral 50 hooks on the side arms, and bearings slideable on the side rods to receive the hooks for supporting the side arms in a plane offset from the longitudinal axis of the front head, said bearings having grooves to 55 cooperate with the side arms for holding the yoke in retaining and releasing positions.

4. In a rock drill, the combination of a

cylinder, a front head for the cylinder, lateral lugs on the front head, a drill steel extending into the front head, side rods for 60 securing the front head to the cylinder, springs on the side rods, a yoke partly encircling the drill steel for retaining said drill steel in the front head, side arms on the yoke, inwardly extending lateral hooks 65 on the side arms, bearings slideable on the side rods between the springs and the lugs, said bearings having transverse apertures to receive the hooks for supporting the side arms in a plane offset from the longitudinal 70 axis of the drill steel, and grooves in the sides of the bearings to cooperate with the side arms for holding the yoke in retaining and releasing positions.

5. In a rock drill, the combination of a 75 cylinder and front head, a drill steel extending into the front head, side bolts securing the front head to the cylinder, bearings on the side bolts, a yoke preventing ejection of the drill steel from the front head, and side arms on the yoke pivoted with their free ends in the bearings, said side arms being held in engagement with the 80 bearings by the resiliency of the side arms and the yoke.

6. In a rock drill, the combination of a cylinder and front head, a drill steel extending into the front head, side bolts securing the front head to the cylinder, bearings slideable on the side bolts, said bearings having longitudinal grooves and transverse 90 apertures, a yoke for retaining the drill steel in the front head, side arms on the yoke, and hooks on the side arms extending into the apertures, said side arms being 95 engaged by the grooves and held in engagement therewith by the resiliency of the side arms and the yoke.

7. In a rock drill, the combination of a cylinder and front head, side bolts securing 100 the front head to the cylinder, a drill steel extending into the front head, means comprising a yoke with side arms for preventing ejection of the drill steel from the front head, bearings on the side bolts pivotally 105 supporting the side arms, and means in the bearings engaging the side rods to hold the yoke in retaining position, said side arms being held in engagement with said means by the resiliency of the side arms and the yoke.

In testimony whereof I have signed this specification.

CHARLES C. HANSEN.
